DESIGN FOR A COMBINED TOILET SEAT AND COVER

Irving Chalfin, Paterson, N. J., and Ira A. Fischer,
New York, N. Y., assignors to Plastic Appliances
Mfg. Corp., New York, N. Y., a corporation of
New York

Application May 13, 1947, Serial No. 139,018

Term of patent 3½ years

(Cl. D4—5)

To all whom it may concern:

Be it known that we, Irving Chalfin and Ira A. Fischer, citizens of the United States of America, and residents, respectively, of Paterson, New Jersey, and New York city, in the county of New York and State of New York, have invented a new, original, and ornamental design for a Combined Toilet Seat and Cover, of which the following is a specification, reference being had to the accompanying drawing, forming part thereof, wherein,

We claim:

The ornamental design for a combined toilet seat and cover, substantially as shown.

IRVING CHALFIN.
IRA A. FISCHER.
